CONDIMENT DISPENSER

Paul E. Brefka, Framingham, Mass., assignor to LDA Inc., Natick, Mass., a corporation of Massachusetts

Filed Apr. 25, 1966, Ser. No. 2,004

Term of patent 14 years

(Cl. D44—6)

FIG. 2

FIG. 1 is a perspective view of a condiment dispenser showing my new design, the view from the opposite side being substantially identical; and

FIG. 2 is a top plan view.

I claim:

The ornamental design for a condiment dispenser, as shown and described.
